US0D1085886S

(12) **United States Design Patent** (10) **Patent No.:** **US D1,085,886 S**
(45) **Date of Patent:** **** Jul. 29, 2025**

(54) **MIXING AND DISPENSING APPARATUS**(71) Applicant: **Veltek Associates, Inc.**, Malvern, PA (US)(72) Inventors: **Arthur L. Vellutato, Jr.**, Malvern, PA (US); **Walter A. Baker**, Chalfont, PA (US)(73) Assignee: **Veltek Associates, Inc.**, Malvern, PA (US)(**) Term: **15 Years**(21) Appl. No.: **29/659,614**(22) Filed: **Aug. 10, 2018****Related U.S. Application Data**

(63) Continuation of application No. 15/705,862, filed on Sep. 15, 2017, now Pat. No. 10,335,812, which is a continuation of application No. 14/643,496, filed on Mar. 10, 2015, now Pat. No. 9,764,342, which is a continuation of application No. 13/974,746, filed on Aug. 23, 2013, now Pat. No. 9,108,208, which is a continuation of application No. 13/239,611, filed on Sep. 22, 2011, now Pat. No. 8,523,017.
